ABSTRACT: Certain mercapto organic acids, such as mercaptoisobutyric acid, provide good antisludging action in photographic processing solutions.

INHIBITION OF SILVERING IN PHOTOGRAPHIC SOLUTIONS

This invention relates to photographic processing solutions and methods. In one of its aspects, it relates to monobath compositions and processes for development of silver images in photographic silver salt layers of photographic elements. In another of its aspects, it relates to the use of mercapto organic acids, particularly alkyl-substituted mercapto organic acids, for the stabilization of monobaths.

Processing of an exposed photographic silver salt layer of a photographic element is well known as discussed, for example, in Mees, "The Theory of the Photographic Process," Third Edition, MacMillan Company, New York, N.Y. (1966).

Developing solutions employed for such purposes which contain silver halide solvents often dissolve undesired concentrations of silver salt from a silver salt layer of a photographic element. This is then reduced by developing agent present to finely divided metallic silver which forms a sludge in the solution. In the case of conventional developers, the solvent action is extended by sodium sulfite which has a weak capacity to dissolve silver halide.

However, in the case of monobaths, especially those which contain thiosulfates, larger quantities of silver salts are dissolved and the deposition of sludge becomes a very serious problem, particularly at high temperatures. The sludge may deposit on parts of the equipment employed for processing, such as rollers, belts, etc., as a scale which may clog orifices or scratch film. It may also deposit as a stain on the surface of films and papers, which lowers photographic quality. Consequently, it is extremely desirable to minimize such deposition.

One method of avoiding deposition of silver sludge has been to use an agent other than thiosulfate, such as certain thio compounds, as a fixing agent. However, it has been found that nonthiosulfate fixing agents tend to lose their activity after an undesirably short time due to aerial oxidation. Further disadvantages often are present in the undesirable odor of certain mercapto compounds.

A number of processes have been proposed to simplify or avoid these problems. For example, U.S. Pat. No. 2,453,346 of Russell, issued Nov. 9, 1948, discloses the use of various sulfur compounds in conjunction with metal salts for stabilizing silver prints. Acidic solutions containing the sulfur compounds and metal salts are applied to silver halide emulsion layers following development of the silver image. In U.S. Pat. No. 2,525,532 of Dreywood, issued Oct. 10, 1950, emulsion layers are developed with a p-methylaminophenol-hydroquinone developer solution containing various sulfur compounds. Following development, the emulsions are treated with acid solutions prior to drying. In U.S. Pat. No. 2,614,927 of Broughton et al., issued Oct. 21, 1952, emulsions containing certain developing agents are processed with alkaline solutions followed by inactivation of the residual silver halide with solutions of sulfur compounds such as thioglycolic acid, thiourea or thiosulfates.

A number of compositions and processes have been proposed to overcome such problems with regard to monobaths. Monobaths are well known as described, for example, in "The Monobath Manual" by Grant M. Haist (1966). In this connection, monobaths are known containing certain mercapto organic acids as fixing agents. For instance, U.S. Pat. No. 2,875,048 of Haist et al., issued Feb. 24, 1959, proposes a monobath composition comprising an alkaline solution of a hydroxylamine or 3-pyrazolidone developing agent and a monothioglycerol, thioglycol, beta-mercaptoproethylamine, N,N-diethyl-beta-mercaptoproethylamine or 2-thiobarbituric acid. U.S. Pat. No. 3,255,008, issued June 7, 1966, to William J. Tefft, discloses monobath solutions containing thioglycolic acid (mercaptoacetic acid), beta-mercaptopropionic acid, mercaptosuccinic acid, and 3-mercaptop-1,2-propanediol. U.S. Pat. No. 3,252,787 to Dave R. Kazen, issued May 24, 1966 discloses the use of thiomaleic or mercaptosuccinic acid in monobath developing and fixing solutions.

Mercaptosuccinic acid, o-mercaptopbenzoic acid, mercaptoacetic acid, and cysteine in monobaths are disclosed by G. M. Haist et al. in "Photographic Science and Engineering," Vol. 5, No. 4, pages 198-203, July-August, 1961.

However, none has been entirely satisfactory as an antisludging agent in photographic processing solutions especially in monobaths. This is especially the case with monobaths which contain a thiosulfate fixing agent as demonstrated in following example 2. Often the solution containing such mercapto compounds becomes undesirably hazy, has undesired particles floating in the solution or has undesired balance in developing and/or fixing action due in part to aerial oxidation within an unsuitably short time.

An object of the invention is accordingly to provide a photographic processing solution and method which is resistant to sludging.

It has been found according to the invention that a liquid photographic processing solution or photographic process employing this solution comprising an antisludging agent which is a mercapto organic acid of the formula:

25

wherein R is hydrogen or lower alkyl, i.e. an alkyl group having one to five carbon atoms such as methyl, ethyl, propyl, butyl, and pentyl; R₁ is a lower alkyl as described; and R₂ and R₃ are each selected from the group consisting of hydrogen; alkyl, e.g. alkyl containing one to 20 carbon atoms, such as methyl, ethyl, propyl, butyl, octyl and eicosyl; amino groups, i.e.

35

wherein R₄ is hydrogen or lower alkyl, as described; hydroxyl; and halogen, i.e. fluorine, chlorine, bromine and iodine; and m is zero or an integer from 1 to 5; provides unexpectedly good resistance to sludging, e.g. resistance to formation of undesired concentrations of colloidal silver or other undesired deposits which can adversely affect processing of an exposed photographic silver salt layer of a photographic element in such processing solution or photographic process. It has been found that compounds within formula I wherein m is 0, such as mercaptoisobutyric acid, are especially suitable antisludging agents for use in liquid photographic processing solutions and in processes employing these solutions. Compounds of described formula I are surprisingly more effective, or, as effective but at lower concentrations than closely related mercaptoacetic acid and 3-mercaptopropionic acid as described in following examples 15, 16, 20 and 21.

Examples of suitable compounds within formula I include:

Thiolactic acid (2-mercaptopropionic acid)

α-Mercaptoisobutyric acid

2-Mercaptobutyric acid

2-Mercapto-2-methylbutyric acid

60 2-Mercapto-3-methylpentanoic acid, and
2,2-Dimethyl-3-mercaptopropionic acid.

One of the embodiments of the invention is a monobath comprising an antisludging agent of formula I as described. In this connection, monobaths are well known, as set out for example in "The Monobath Manual," by Grant M. Haist, 1966. Any monobath and/or monobath process can be employed according to the invention in which it is desirable to have resistance to sludging and in which compounds within formula I as described are effective.

70 Compounds within formula I, as described are especially effective in monobaths and/or monobath processes employing such monobaths which contain a silver halide developing agent and a thiosulfate fixing agent, i.e. so-called thiosulfate monobaths described, for example, in U.S. Pat. No. 3,173,789 of King and Moran, issued Mar. 16, 1965.

The antisludging agents within formula I are also effective in a wide range of other photographic processing solutions and in general can be employed in photographic processing solutions and/or processes where resistance to sludging is desired. For instance, while compounds within formula I are especially effective in thiosulfate monobaths, they can also be employed in a developer solution, a development activator solution, a fixing solution, a stabilizing solution, a gelatin hardener solution, a solution designed for rapid access processing, e.g. thiocyanate solutions, such as alkali metal thiocyanate and/or ammonium thiocyanate solutions, and the like. Solutions of these types are well known and described, for instance, in "The Theory of the Photographic Process," Mees et al., Third Edition, 1966, MacMillan Company.

Typical processing solutions according to the invention are aqueous solutions, but other solvents can be employed if desired, or can be employed in combination with water. For instance, it can be suitable to employ organic solvents, such as an organic amine and/or hydroxyl amine solvents, e.g. propyl amine, butyl amine, 2-aminoethanol, 2-methylaminoethanol, 2-ethylaminoethanol, diethanol amine(2,2'-iminodiethanol), 2-aminopropanol, morpholine, and the like. Such organic solvents can have other affects than solvent action, e.g. they can be development activators.

The exact quantity of the antisludging agent or antisilvering agent within formula I needed is dependent upon a number of factors, such as pH and silver solvency of the processing solution, temperature of processing, nature and silver coverage of the photographic element processed, degree of exhaustion of the processing solution, and other factors. Thus, certain developer solutions can require considerably less of the described antisludging agent than a monobath. In general, developers require less than 0.5 gram of the described antisludging agent per liter of processing solution for normal usage. Usually 0.05 to 0.5 gram per liter is sufficient, but highly alkaline monobaths for high temperature processing may require 5 to 20 grams per liter of solution.

The ordinarily employed silver halide developing agents for producing a developed silver image can be used in solutions and processes of the invention. Especially useful results have been obtained using the well known 3-pyrazolidone developing agents. Typical of pyrazolidone developing agents useful in the monobath compositions of the invention are set out in British Pat. No. 930,572, including 1-phenyl-3-pyrazolidone, 1-phenyl-4,4-dimethyl-3-pyrazolidone, 1-phenyl-5-methyl-3-pyrazolidone, 1-phenyl-4-methyl-3-pyrazolidone, 1,5-diphenyl-3-pyrazolidone, 1-p-tolyl-3-pyrazolidone, 1-phenyl-2-acetyl-4,4-dimethyl-3-pyrazolidone (acetyl group hydrolysis off to yield active developing agent), 1-p-hydroxyphenyl-4,4-dimethyl-3-pyrazolidone, 1-(2-benzothiazolyl)-3-pyrazolidone, 3-acetoxy-1-phenyl-3-pyrazolidone (acetoxy group hydrolysis off to yield active developer), etc. These 3-pyrazolidone developing agents are particularly useful and they can be incorporated partly or wholly within the photographic element undergoing development. However, for rapid monobath processing, it is desirable to generally have sufficient pyrazolidone developing agent in the aqueous developing solution to effect rapid processing. Other black-and-white photographic developing agents which can be employed alone or in combination with the 3-pyrazolidone include, for example, polyhydroxy benzenes, such as hydroquinone developing agents, e.g. hydroquinone, alkyl-substituted hydroquinone, such as t-butylhydroquinone, methylhydroquinone, dimethylhydroquinone; catechol and pyrogallol; chloro-substituted hydroquinones, such as chlorohydroquinone, or dichlorohydroquinone; alkoxy-substituted hydroquinone, such as methoxy or ethoxy hydroquinone; aminophenol developing agents, such as N-methyl-p-aminophenol and 2,4-diaminophenols; ascorbic acid developing agents; N-methyl-p-aminophenol sulfate, pyrazolones such as 4-aminopyrazolone; etc. The concentration of the developing agent in the monobath composition can be varied, depending upon the particular photographic material undergoing development. As indicated above, the 3-pyrazolidone developing agents are

particularly useful, since they can be incorporated directly into the photographic material either in a layer contiguous to the emulsion layer or in the emulsion layer itself (particularly where a development precursor is used, such as 3-acetoxy-1-phenyl-3-pyrazolidone).

The photographic processing solutions, especially the monobath compositions, of the invention can comprise any of the conventional water-soluble fixing agents, typically thiosulfate fixing agents, such as alkali metal, e.g. sodium, potassium, and lithium thiosulfates, ammonium thiosulfate, etc. The concentration of the thiosulfate compound can be varied, but it is important to have the concentration sufficiently high to fix or stabilize the desired concentration of the unexposed silver halide. For the purposes of our invention, we have found in a monobath that the thiosulfate concentration should be at least about 80 grams per liter of monobath. The maximum concentration of thiosulfate is primarily a function of the concentration of the silver halide in the emulsion being processed. Frequently, concentrations as high as 160 grams of thiosulfate per liter of monobath composition can be employed and good quality prints can be produced in 5 seconds or less using such compositions. Of course, if the concentration of silver halide in the emulsion is increased, then it is possible that amounts of thiosulfate in excess of 160 grams per liter can be employed. Overfixing is of course to be avoided.

It can be advantageous in some cases to have an antifoggant present in the monobath composition and/or in the photosensitive element employed in the practice of the invention. Suitable antifoggants include organic antifoggants, such as benzotriazole, benzimidazole, 2-mercaptopbenzimidazole and mercaptotetrazole antifoggants. Inorganic antifoggants, including potassium bromide, potassium iodide and/or sodium bromide, can be employed in the photosensitive element and/or monobath composition of the invention. Any suitable amount of antifoggant can be employed, depending on the components of the monobath composition, the photosensitive element, and the like.

Processing according to the practice of the invention can be carried out under any suitable conditions, usually ambient conditions, e.g. about 20° C. to about 30° C. However, higher temperatures can be employed if desired. Particularly where rapid processing is to be carried out, temperatures about 60° C. can be used.

The time for processing employing the compositions and processes of the invention can vary from about a second to several minutes or more depending on the desired image, processing conditions and the like.

Any development activator and any suitable concentration of development activator can be employed in the solutions of the invention which provides the desired alkalinity or pH to effect the desired development. Typical development activators include inorganic development activators such as sodium hydroxide, potassium hydroxide, lithium hydroxide, sodium carbonate, and potassium carbonate, as well as organic activators, such as organic amines, e.g. hydroxyalkyl amines, such as ethanolamine, morpholine, propanolamine, and the like. The pH of solutions of the invention, e.g. monobaths, can vary over wide ranges, but in general a pH of at least 9 is employed, e.g. preferably about 10.0 to about 13.

The compositions and processes of the invention are suitable for developing and fixing a wide variety of photosensitive emulsions, especially silver halide-gelatin photosensitive emulsions. The photosensitive emulsions which can be developed and fixed with the compositions and processes of the invention include those which are nonspectrally sensitized, such as X-ray type emulsions, or emulsions which are orthochromatic, panchromatic, infrared sensitive, and the like, containing spectral sensitizing dyes. Spectral sensitizers which can be used in a photosensitive emulsion processed according to the invention include cyanines, mercocyanines, styryls, and the like.

The photographic elements employed in the practice of the invention can be sensitized by using any of the well-known

techniques used in emulsion making, e.g. by digesting with naturally active gelatin or various sulfur, selenium, noble metal and/or gold compounds.

The photosensitive emulsions employed in the practice of the invention, as well as the solutions of the invention, can contain various photographic addenda, especially those known to be beneficial in photographic compositions. The types of addenda and amounts to be employed can be determined by those skilled in the art. Suitable addenda include, for example, hardeners, e.g. those set out in British Pat. No. 974,317; buffers which maintain the desired pH level including various sulfonamides, borates, and boraxes; coating aids; plasticizers; speed-increasing addenda, such as quaternary ammonium salts and alkylene oxide polymers, and various stabilizing agents, such as sodium sulfite.

Various colloids can be used alone or in combination as vehicles or binding agents where one is used in the photosensitive emulsions and elements employed in the practice of the invention. Among such materials are the natural and/or synthetic binding materials generally employed for this purpose including, for example, gelatin, colloidal albumin, water-soluble vinyl polymers, and polysaccharides, polyvinylpyrrolidone and the like. In addition to the hydrophilic colloids, the vehicle or binding agents can contain dispersed polymerized vinyl compounds, particularly those which increase the dimensional stability of photographic materials. Suitable synthetic polymers of this type include water-insoluble polymers of alkyl acrylates and methacrylates, acrylic acid, sulfoalkyl acrylates or methacrylates and the like.

The silver salts processed according to the invention include any of the photosensitive silver salts, such as any of the photosensitive silver halides. Suitable silver halides include, for example, silver bromide, silver iodide, silver chloride or mixed halides, such as silver chlorobromide, silver bromoiodide, and the like. Preferred silver halides are those in which the halide comprises at least 50 mole percent chloride. The silver halides used can be those which form latent images predominately on the surface of the silver halide grains or those which form latent images inside the silver halide crystals, as well as direct positive emulsions.

The photosensitive emulsions processed according to the invention can be coated on a wide variety of supports. Typical supports include those generally employed for photographic elements, including various films, such as cellulose acetate films, cellulose nitrate films, polycarbonate films, and related materials, papers, such as paper supports coated with resinous materials, e.g. coated with polyethylene, polypropylene and/or polyethylenebutene copolymers, glass, metal, and the like.

Another embodiment of the invention comprises a method of preventing a sludging in a liquid photographic processing solution by addition of an antisludging agent to said solution the improvement comprising employing as said antisludging agent a mercapto organic acid of the formula:

wherein R is hydrogen or lower alkyl; R₁ is lower alkyl; and R₂ and R₃ each selected from the group consisting of hydrogen, alkyl, amine, hydroxyl and halogen; m is zero or an integer from 1 to 5. This process is especially useful in preventing sludging in monobaths, e.g. thiosulfate monobaths, as

described.

The following examples are included for a further understanding of the invention.

EXAMPLE 1

Mercaptoisobutyric acid at 0.2 gram per liter is added to the following monobath:

Sodium sulfite	50 grams
Hydroquinone	12 grams
Phenidone (1-phenyl-3-pyrazolidone)	4 grams
Sodium hydroxide	4 grams
Sodium thiosulfate (5 H ₂ O)	110 grams
Glutaraldehyde bis(sodium bisulfite)	5 grams
Water to make	1 liter

15

One 12-inch 35-mm. strip of exposed film having a high-speed, fine-grained silver chlorobromide emulsion layer is developed for 6 minutes at about 20° C. in 500 ml. of the monobath solution. The solution is clear and colorless before the film is processed and the solution is clear and colorless after 24 hours after the film is processed. No sludging is apparent.

EXAMPLE 2

25 This is a comparative example demonstrating advantages of the invention.

Development of exposed film of example 1 is repeated in a monobath as in example 1 except no antisludging compound is present. The clear and colorless monobath solution becomes hazy immediately after processing the film. Within 2 hours, silver sludge begins to settle to the bottom. A very heavy tan-colored sludge deposits from the hazy solution after 24 hours.

35

EXAMPLE 3

This is a comparative example serving to further illustrate the effectiveness of antisludging agents according to the invention.

40 Three 12-inch 35-mm. strips of film as described in example 1 with sensitometric exposures are each developed for 15 minutes at about 20° C. in 500 ml. of the following developer:

p-methyl aminophenol sulfate	5.0 grams
Sodium sulfite, desiccated	100.0 grams
Sodium metaborate	2.0 grams
Sodium thiocyanate	1.0 gram
Potassium bromide	0.5 gram
Water to make	1 liter

50 A very heavy silver scum forms on the film emulsion during development and silver sludge begins to form in the developer solution. After 21 days at room temperature, the solution clears, but a metallic gray sludge has precipitated.

55

EXAMPLE 4

Mercaptoisobutyric acid (0.5 gram) is added to 500 milliliters of the developer described in example 3. Three film strips are processed as in example 3. After development, the film surface is entirely free of any silver scum. The developer solution is clear and colorless without any appearance of sedimentation. After 21 days at room temperature, the used developer is clear and colorless, still without any evidence of silver precipitation.

65 Repeating example 1, but with the compounds used below the results are as follows:

TABLE I

Example	Compound	Condition 24 hrs. after use, sludge and nature
5	L-cysteine (free base)	Almost clear, colorless heavy tan sludge.
	$\text{HS}-\text{CH}_2-\text{CH}(\text{NH}_2)-\text{COOH}$	
6	Isothiureidoacetic acid	Hazy, pale yellow tan, floating particles, some finely divided sludge.

Table I—Continued

Example	Compound	Condition 24 hrs. after use, sludge and nature
7		Hazy, brown, floating particles, heavy brown sludge.
8		Clear, yellow brown compound, particles, but no sludge.
9		Clear, yellow brown, no sludge.
10		Cloudy, yellow brown, very slight sludge.
11		Hazy, light tan, floating particles, heavy tan sludge.
12		Hazy, pale yellow, floating particles, some sludge.
13		Hazy, light yellow, floating particles, some sludge.
14		Clear, colorless, heavy tan-colored sludge.
15		Hazy, tan-colored, dark brown sludge.
16		Cloudy, light red-brown floating particles heavy red-brown sludge.
17		Clear, colorless.

The following monobath is prepared:

1-phenyl-3-pyrazolidone	4.0 grams
sodium sulfite (anhydrous)	50.0 grams
hydroquinone	12.0 grams
sodium hydroxide	4.0 grams
sodium thiosulfate (5H ₂ O)	110.0 grams
water to make	pH=10.3
	1.0 liter

70 Five hundred-milliliter portions of this monobath are placed in graduated cylinders. One-hundredth of the molecular weight (in grams) of each potential antisludging compound is added to sufficient 5 percent sodium hydroxide to neutralize the acidity of the compound and to insure an alkaline solution. 75 This solution is then added to the 500 ml. portions of the monobath in the cylinders. The pH of the monobath is adjusted to 10.3 with glacial acetic acid.

The following compounds were tested for their effectiveness in inhibiting the formation of sludge after the addition of 4.5 ml. of a melted silver chloride photographic emulsion (353 mg. silver) to each portion of the monobath solution, as shown in table II.

Visual observations of solution color and clarity are made (1) before the addition of the silver chloride emulsion, (2) immediately after the addition of the emulsion, and at intervals of (3) 48 hours. These observations are listed in table II.

TABLE II
The Effectiveness of Antisludging Compounds

Example	Compound Added	After Emulsion Addition	After 48 Hours
	None	Clear Colorless	Clear Colorless
	None (Silver Added)	Hazy Light tan	Hazy, tan grayish tan sludge
18	2-Mercaptoisobutyric acid	Clear Colorless	Clear Colorless
19	Mercaptosuccinic acid	Clear Colorless	Hazy gray floating particles black sludge

20	Mercaptoacetic acid	Cloudy yellow-brown	Opaque, brown, brown-black sludge
21	3-Mercaptopropionic acid	Opaque grayish brown	Opaque brown dark brown sludge
22	4-Mercaptobutyric acid	Clear Yellowish tan color	Opaque Dark brown sludge
23	2-Mercaptopropionic acid (Thiolactic acid)	Clear Pale Yellow	Clear Pale Yellow
24	2-Mercaptoethanol	Opaque Tan dispersion	Opaque Gray-black, Gray-black sludge

(All were clear before addition of the emulsion and all were colorless at that point except
o-mercaptopbenzoic acid (pale straw) and 4-mercaptopbutyric acid (pale yellow).)

25 Examples 18 through 24 are repeated, but using 1.0 gram of the antisilvering compound in 500 ml. of the developer, with the following results:

TABLE III

Example	Compound	Before emulsion added	After emulsion added	After 120 hours
25	None	Clear, colorless	Cloudy, faint tan	Clear, heavy tan sludge, plating on sides.
25	L-cysteine (free base)	do	Clear, faint tan	Clear, yellow black, no plating.
	$\text{HS}-\text{CH}_2-\underset{\text{NH}_2}{\text{CH}}-\text{COOH}$			
26	4-S-thiuroniumbutane sulfonate	do	Clear, pale yellow	Hazy, light yellow with floating particles, heavy sludge, slight plating.
	$\text{H}_2\text{N}^+ \quad \text{H}_2\text{N}$ =C-S-CH ₂ -CH ₂ -CH ₂ -SO ₃ -			
27	3-S-thiuroniumbutane sulfate	Clear	Clear	Cloudy, brown solution, floating particles, brown sludge, no plating.
	$\text{CH}_3-\text{CH}-\text{CH}_2-\text{CH}_2-\text{SO}_3-$ S-C NH ₂ NH ₂ +NH ₂			
28	Iothiureidopivalic acid	Clear, colorless compound slightly insoluble.	Hazy, colorless	Hazy yellow color, heavy gray sludge, some plating.
	$\text{H}_2\text{N}^+ \quad \text{CH}_3 \quad \text{O}^-$ =C-S-CH ₂ -C(CH ₃) ₂ -C=O			
29	2-S-thiuroniummethane sulfonate	Hazy, colorless	Hazy, light yellow	Clear, colorless, few floating particles, heavy reddish sludge.
	$\text{H}_2\text{N}^+ \quad \text{H}_2\text{N}$ =C-S-CH ₂ -CH ₂ -SO ₃ -			
30	3-S-thiuroniumpropane sulfonate	Clear, colorless	Clear, pale yellow	Hazy, light yellow solution with floating particles, dark brown sludge, no plating.
	$\text{H}_2\text{N}^+ \quad \text{H}_2\text{N}$ =C-S-CH ₂ -CH ₂ -CH ₂ -SO ₃ -			
31	Alpha-thio-2-furanpyruvic acid	Clear, yellow-tan color.	Hazy, yellow-tan color.	Opaque, cinnamon brown color, gray sludge and plate, plated silver on sides.
	$\text{O} \quad \text{CH}=\text{C}-\text{COOH}$ S H			

Table III—Continued

Example	Compound	Before emulsion added	After emulsion added	After 120 hours
32.	DL-penicillamine	Hazy, colorless	Hazy, colorless	Hazy, faint yellow tint, few particles on bottom, no plating.
33.	Mercaptoisobutyric acid	Clear, colorless	Clear, colorless	Clear, colorless, no plating, or sludge.
34.	Beta-sodium thioglucose	do	Hazy, colorless	Clear, yellow solution, heavy gray sludge, considerable plating.
35.	Beta-phenyl-alpha-mercaptopropanoic acid	Yellow, white particles	Hazy, yellow, white	Hazy, brown solution, some floating particles, gray-brown sludge, considerable plating.
36.	Isothiureidoacetic acid	Clear, white compound particles	Yellowish, white compound	Clear colorless, floating particles, dark brown sludge, no plating.
37.	Beta-isothiureidopropionic acid	Clear, colorless	Clear, pale yellow	Pale yellow, floating particles, heavy brown sludge, no plating.
38.	Gamma-isothiureidobutyric acid	Clear, colorless, some compounds not soluble	Clear, colorless	Clear, yellow brown, brown sludge, dense gray silver plate on sides of cylinder.

The invention has been described in detail with particular reference to preferred embodiments thereof, but it will be understood that variations and modifications can be effected within the spirit and scope of the invention as described hereinabove and as defined in the appended claims.

We claim:

1. A liquid photographic processing solution comprising an antisludging agent which is a mercapto organic acid of the formula:

wherein R is hydrogen or lower alkyl; R₁ is lower alkyl; and R₂ and R₃ are each selected from the group consisting of hydrogen, alkyl, amine, hydroxyl and halogen; m is zero or an integer from 1 to 5.

2. A liquid photographic processing solution as in claim 1 comprising a monobath.

3. A liquid photographic processing solution as in claim 1 comprising a monobath containing a silver halide developing agent and a thiosulfate fixing agent.

4. A liquid photographic processing solution as in claim 1

50 comprising a development activator solution.

5. A liquid photographic processing solution as in claim 1 comprising a developer solution.

6. A liquid photographic processing solution as in claim 1 wherein said mercapto organic acid is mercaptoisobutyric acid.

7. A liquid photographic processing solution as in claim 1 comprising a monobath and wherein said mercapto organic acid is mercaptoisobutyric acid.

8. A liquid photographic processing solution as in claim 1 comprising a monobath containing a thiosulfate fixing agent and wherein said mercapto organic acid is mercaptoisobutyric acid.

9. A liquid photographic processing solution as in claim 1 comprising a monobath containing 0.05 to 0.5 gram per liter of said mercapto organic acid.

10. A liquid photographic processing solution as in claim 1 comprising a monobath containing:

- mercaptopropanoic acid,
- alkali metal thiosulfate,
- a silver halide developing agent,
- a development activator, and
- a gelatin hardening agent.

11. A liquid photographic processing solution as in claim 10 wherein said gelatin-hardening agent is a glutaraldehyde

70

bis(alkali metal bisulfate).

12. A liquid photographic processing solution as in claim 1 also comprising a 3-pyrazolidone developing agent.

13. A photographic method comprising developing and fixing an image in an exposed photographic silver salt layer of a photographic element by contacting said photographic silver salt layer with a monobath resistant to sludging containing a mercapto organic acid of the formula:

wherein R is hydrogen or lower alkyl; R₁ is lower alkyl; and R₂ and R₃ are each selected from the group consisting of hydrogen, alkyl, amine, hydroxyl and halogen; m is zero or an integer from 1 to 5.

14. A photographic method as in claim 13 wherein said monobath comprises a thiosulfate fixing agent, a silver halide developing agent and mercaptoisobutyric acid.

15. A photographic method as in claim 13 wherein said

photographic silver salt layer is a photographic silver halide emulsion layer.

16. A photographic method comprising developing and fixing an image in an exposed photographic silver salt layer of a photographic element containing a silver halide developing agent by contacting said photographic element with a photographic processing solution resistant to sludging comprising:

- a. a development activator,
- b. a silver halide fixing agent, and
- c. a mercapto organic acid of the formula:

wherein R is hydrogen or lower alkyl; R₁ is lower alkyl; and R₂ and R₃ are each selected from the group consisting of hydrogen, alkyl, amine, hydroxyl and halogen; m is zero or an integer from 1 to 5.

UNITED STATES PATENT AND TRADEMARK OFFICE
CERTIFICATE OF CORRECTION

PATENT NO. : 3,628,955

DATED : December 21, 1971

INVENTOR(S) : Grant M. Haist and David A. Pupo

It is certified that error appears in the above-identified patent and that said Letters Patent are hereby corrected as shown below:

Column 1, line 73, "3,252,787" should read
---3,252,797---.

Signed and Sealed this
sixteenth Day of March 1976
